LLOYD G. COPEMAN, OF FLINT, MICHIGAN.

REFRIGERATOR CABINET AND METHOD OF CONTROLLING THE TEMPERATURE THEREIN.

Application filed November 18, 1926. Serial No. 149,101.

This invention relates to refrigerator cabinets and method of controlling the temperature therein. It has to do particularly with cabinets of the larger type, such as ice-cream cabinets, containing a plurality of units immersed in a body of brine or other non-freezing solutions.

Heretofore, in the manufacture of ice-cream cabinets or the like utilizing mechanical refrigeration, it has been customary to construct the main cooling unit of the cabinet of a suitable container which has been filled with brine, or other non-freezing solutions, and in which has been positioned suitable direct expansion coils for effecting heat absorption and cooling of the brine. Various attempts have been made to cool the various compartments of ice cream cabinets or similar structures with direct expansion coils and also with brine coils, but the standard cabinets utilizing a body or bodies of brine have been found most satisfactory, and have been generally used up to the present time.

This method of coiling the container units in ice-cream cabinets, or the like, by the use of a body of brine controlled by suitable refrigerating coils therein, has been very objectionable for two main reasons, one being the necessity of a very expensive construction, and the other being the liability of the brine seeping and eating through the joints of the container shell, and into the container units for receiving the ice-cream cans, etc. Much trouble has been experienced along this line where compartments have been used for brick ice-cream, bottled goods, etc., which have necessitated the use of picks, and other sharp instruments in the separation thereof, with the result that holes are quite frequently punched in the walls of the container units allowing the brine to seep in, and thus make the cabinet unfit for use. Another great disadvantage of this type of cabinet, as has been heretofore used, is the buoyancy of the container cans when inserted in the main container unit due to the specific gravity of the brine. In cabinets having a large number of these container sleeves for units, this buoyancy has become a very serious problem, especially where all the shells are formed integrally with the cover and inserted in the brine at one time.

It is the primary object of this invention to provide a refrigerating cabinet of the type

utilizing brine, or other non-freezing substance, as the heat absorbing and hold-over medium, which cabinet is so constructed as to retain all the benefits of the use of the brine, and at the same time making the unit containers of the cabinet positively leak-proof. 55 Another object of the present invention has to do with the provision of a refrigerating cabinet, the unit containers or compartments of which are formed separately, and may be removed and replaced at will without effecting the other units or construction of the cabinet. A further feature of the present invention has to do with the provision of individual container units, each having a specific gravity greater than the non-freezing solution, and which units are formed of a material which is a relatively good conductor and a good hold-over. By this structure I have made it possible to completely build an ice-cream cabinet or the like, of the standard 70 form, and which is relatively light and compact, whereby such cabinet may be shipped to the user and the two hold-over mediums, namely, the non-freezing solution and the stone container units inserted at the place of 80 use, the container units requiring no other labor than merely placing them in the proper apertures and allowing them to settle to the bottom of the tank.

In the drawings:

Fig. 1 is a vertical, longitudinal section taken through a refrigerating cabinet, embodying my novel invention, and illustrating the preferred arrangement of parts whereby the brine is cooled by the initial refrigerating coils and the stone container units are in turn cooled by the brine, the brine and the container units serving to stabilize the temperature in the cabinet and the container units serving to absorb the heat from the contents 95 of the container units.

Fig. 2 is a horizontal section taken through the cabinet, illustrated in Fig. 1, and showing the conventional arrangement of the elements shown in Fig. 1.

Fig. 3 is a fragmentary sectional view illustrating the manner of inserting the stone container units in the brine tank, each unit being inserted separately and sinking to the bottom 105 of the tank by its own weight.

In the drawings I have illustrated my invention in connection with a standard ice-cream-cabinet of a type utilizing expansion

coils immersed in a body of liquid brine. The drawings are somewhat conventional and diagrammatic, and it will be understood that my invention may be embodied in any type 5 of cabinet having one or more container units for receiving articles to be cooled, and utilizing brine as a hold-over medium, and to assist in cooling and absorbing the heat from the contents of the container or containers. 10 In Fig. 1 I have shown an ice-cream cabinet which may be generally designated 1, and which is made up of the usual frame member 2 and cork or other insulation 3.

As in refrigerating cabinets of this standard type, the outside cabinet or jacket is preferably lined with a metal lining 4. A brine tank 5 of suitable size is fitted or supported within the refrigerating cabinet, it being understood that this brine tank may be inserted 20 in the cabinet at the place of manufacture or at the place of use. The brine tank, of course, is made of suitable metal to prevent corrosion and is fabricated and the joints sealed in such a manner as to prevent leaking of the 25 brine.

Suitable refrigerating coils 6 are positioned within the brine tank, and these coils are in turn connected by suitable conduits 7 to any standard refrigerating apparatus 30 whereby to effect expansion and compression of the refrigerating gases. It will be understood that the refrigerating coils 6 may be positioned in any desired part of the brine tank to effect the best results in accordance 35 with the position of the container units.

The top of the brine tank may be designated 8, and is provided with a plurality of apertures 9. These apertures are designed to receive suitable container units and are adapted to have a close fit with relation to such units, instead of being soldered or otherwise secured to the container units, as has been done in the past. Where the container units have been soldered, or otherwise secured, to the brine tank top, in prior construction, it has been necessary to utilize extremely 40 rigid and compact structure for holding the top with its rigidly secured brine tanks in position, as the buoyancy of the brine tanks, 45 due to the specific gravity of the brine, has created considerable upward pressure; and 50 thus placing a great strain upon the various joints.

Instead of utilizing a metal container unit 55 to receive the ice-cream, or other materials, and to keep out the brine, I utilize relatively heavy container units made of artificial stone. These container units may be designated 10, and are preferably formed of an oxy-chloride 60 cement which may be made up of a mixture of magnesium oxide, and fine silica or sand, to which may be added enough magnesium chloride in solution whereby to make a mixture that may be easily poured into suitable 65 moulds. The pores of these cast stone con-

tainers may be filled with a suitable sealing material, such as paraffin, but this is not necessary and it does not form a part of the present invention. These cast stone units may be manufactured separately from the refrigerating cabinet and shipped to the point of use, or they may be easily manufactured at the place of use. The place of manufacture is immaterial except that it makes it unnecessary to build the refrigerating cabinet complete with the container units, and it is only necessary to completely form the relatively light cabinet and ship it to the place of use where the brine may be poured into the tank and the relatively heavy container units inserted in the respective apertures and allowed to sink to the bottom of their own weight. Each container unit is, therefore, independent of the other and independent of the top, whereby if necessary, it may be easily replaced without removing the entire top structure. 70 80 85

The container unit, being formed of stone, presents an excellent conductor whereby the brine and the refrigerating medium may perform the function of absorbing the heat from the articles placed in the container units with the greatest possible efficiency. Each container unit also serves as a "hold-over" unit, thus tending to maintain the temperature of 90 95 the cabinet at a constant level.

It will thus be obvious that I have provided simple, inexpensive container units for refrigerating cabinets of the type utilizing brine. These container units are formed of 100 stone, increase the efficiency of the refrigerating cabinet, positively prevent any leakage of the brine within the container units, and cost much less to build, in that the artificial stone costs about a cent and a half a pound, whereas the non-corrosive metals heretofore used have cost about thirty cents a pound. No expensive or heavy clamping devices are needed to hold the top of the brine tank in place, as when my relatively heavy container units are used there is no pressure whatever transmitted to the top of the brine tank. If 105 for any reason any one of the container units should be defective in manufacture, it may be easily replaced by simply removing the 110 same and replacing with another unit.

What I claim is:

1. A refrigerating cabinet, comprising an apertured brine tank refrigerating coils positioned therein for cooling the brine, and a removable storage compartment of cast stone 120 freely positioned in said aperture and within the tank, said storage compartment being of such weight as to sink within the brine.

2. A refrigerating cabinet, comprising a 125 cabinet structure, a tank adapted to contain a non-freezing solution, a top for the tank containing an aperture, and a cast stone container unit for receiving ice cream cans insertable within said and positioned by said 130

aperture for forming a storage compartment in the non-freezing solution, said unit closely fitting and filling the aperture but being completely independent of the top.

5 3. A refrigerating cabinet, comprising a refrigerating tank adapted to contain a non-freezing solution, a refrigerating coil positioned within said tank for cooling said solution, and a container forming a storage compartment for ice cream cans and freely positioned within said tank, said container being of uniform diameter and extending to the bottom of the tank, and being relatively heavy and formed of a material of relatively

15 high heat conductivity.

4. A refrigerating cabinet, comprising a tank adapted to contain a non-freezing solution, a refrigerating coil positioned within said tank for cooling the solution, and a container unit forming a storage compartment for ice cream cans and positioned in said non-freezing solution, said container unit being formed of a material of relatively high conductivity and being relatively heavy whereby

25 it will sink in said non-freezing solution of its own weight.

5. An ice-cream cabinet or similar structure, comprising a relatively light cabinet built up of an insulating material, and provided with a brine tank containing a fixed supply of brine, apertures in the top of said brine tank and cast stone storage containers for ice cream cans adapted to be separately inserted in said apertures and freely remov-

able therefrom, and a refrigerating coil positioned within said brine tank for directly cooling the brine and indirectly cooling the stone containers, said containers being of substantially uniform diameter and extending to the bottom of the tank.

6. An ice-cream cabinet or similar structure, comprising in combination a tank adapted to contain a non-freezing solution, a top for said tank containing a plurality of apertures, a refrigerating coil positioned within said tank for cooling the solution, and imperforate storage container units for receiving ice cream cans adapted to be inserted through said apertures, said containing units being positioned by but held in said non-freezing solution independently of said top.

7. An ice-cream cabinet or similar structure, comprising in combination a tank adapted to contain a fixed supply of non-freezing solution, a top for said tank containing a plurality of apertures, refrigerating means positioned within the tank for cooling the solution, and completely independent imperforate storage container units for receiving ice cream cans adapted to be separately inserted in said apertures and into said brine and freely removable therefrom, said storage units being of uniform diameter and extending substantially to the bottom of the tank.

In testimony whereof I have affixed my signature.

LLOYD G. COPEMAN.
